UNITED STATES PATENT OFFICE.

CHARLES W. COLLINS, OF TIFFIN, OHIO.

PUMPING MECHANISM.

1,116,389.

Specification of Letters Patent. Patented Nov. 10, 1914.

Application filed October 13, 1913. Serial No. 794,955.

To all whom it may concern:

Be it known that I, CHARLES W. COLLINS, a citizen of the United States, residing at Tiffin, in the county of Seneca and State of Ohio, have invented certain new and useful Improvements in Pumping Mechanisms, of which the following is a specification, reference being had to the accompanying drawings.

10 This invention relates to certain improvements in pumping mechanisms, and the object of the invention is, in part, to provide a device of this general character having novel and improved means whereby the mechanism is prevented from becoming inoperative through freezing; and, in part, to provide a device of this general character having means of a novel and improved character whereby the water to be conveyed or elevated by the mechanism is agitated in order to purify the same and whereby the walls of the cistern or the like from which the water is conveyed or elevated are washed.

25 The invention consists in the details of construction and in the combination and arrangement of the several parts whereby certain important advantages are attained and the device is rendered simpler, less expensive and otherwise more convenient and advantageous for use, all as will be hereinafter more fully set forth.

The novel features of the invention will be carefully defined in the appended claims.

35 In order that my invention may be better understood, I will now proceed to describe the same with reference to the accompanying drawings, wherein—

40 Figure 1 is a view partly in section and partly in elevation illustrating a pumping mechanism constructed in accordance with my invention; and Fig. 2 is a sectional view taken on the line 2—2 of Fig. 1.

45 As disclosed in the accompanying drawings, 1 denotes a cistern, well or the like in which the water stands and 2 denotes a pump cylinder of predetermined length in which is suitably mounted for recurrent movement through the action of the operating member 3, the rod 4 having suitably secured at its lower end the piston 5 being herein shown as comprised of two concave cups, preferably of leather having their con-

vex sides in contact thus making a double cup or solid piston.

50 While the drawings disclose the operating member 3 for the pump in the nature of a hand operated lever, I do not wish to be understood as limiting myself in any way as to the specific means for operating the pump, as the means disclosed is only conventional as it is the particular purpose of my invention to be employed in connection with a pump operated from a suitable source of power such as a windmill or other motor.

55 Adjacent its upper end the cylinder 2 is provided with an air inlet 6 under control of the check valve 7 and in such upper portion of the cylinder 2 and preferably in the upper head thereof is provided a petcock 8 whereby the air pressure created within the cylinder above the piston 5 may be regulated. In communication with the cylinder adjacent the lower portion thereof and below the piston 5 is the pipe 9 which serves both as the induction and eduction port for 70 the cylinder, such pipe 9 being in communication with the pipe 10 which leads to both the water pipe 11 leading from the cistern 1 or other source of water supply and to the discharge pipe 12, the flow through the pipe 10 being under control of the check valves 75 14 and 15 interposed therein at either side of the pipe 9 the check valve 14 preventing back flow of the water in the pipe 12 on the inward thrust of the piston 5, while the check valve 15 serves to prevent the admission of air within the cylinder 2 upon the outward stroke of the piston 5 which stroke results through suction in the drawing of the water from the cistern 1 or other source 80 85 of supply within the cylinder 2 in a manner which is believed to be obvious.

90 The water pipe 11 is directed within the cistern 1 to a predetermined point below the water line therein and is in communication 95 with the cylinder or enlarged portion 16 of the air line 17 which air line or pipe 17 is directed in such a manner as to communicate with the cylinder 2 at the upper portion thereof and above the piston 5. The lower 100 portion of the water pipe 11 is provided with a depending branch 18 having interposed therein a check valve 19, the water within the cistern 1 being adapted to enter

within the water pipe 11 through the branch 18 upon the outward stroke of the piston 5, said check valve 19 serving to prevent the escape of air therethrough, as is believed to 5 be obvious.

Upon the outward stroke of the piston 5, the air admitted within the cylinder 2 above the piston 5 through the air inlet 6 will be forced through the air line or pipe 17 and 10 within the cylinder or enlarged portion 16 which is preferably of a diameter substantially equal to twice the diameter of the air line or pipe 17 and thus assist in the conveyance or elevation of the water within the 15 water pipe 11 to within the cylinder 2 until the air reaches the vent 21 through which the air is discharged into the cistern thus agitating the water and serving to purify the water and clear it from insect life. As 20 herein shown the vent comprises a pipe member angularly directed from the pipe line 11 and rotatably supported thereby so that the resistance offered by the water to the escaping air will cause the vent pipe 21 25 to travel about the pipe 11 whereby an effective agitation of the water within the cistern is assured and this vent pipe 21 is of such a length as to terminate in close proximity to the wall of the cistern whereby the 30 combined action of the air and water assures a washing of the cistern while it tends to soften the water and produces a more sanitary condition. In order to increase the efficiency of the action of the air discharged, I 35 find it best to provide at the free end of the vent pipe 21, the reticulated nozzle 22, as is clearly shown in the drawings. It is to be observed that the enlargement 16 of the air line or pipe 17 is of a greater capacity than 40 that of the water line or pipe 11 and of such a capacity relative to the capacity of the water line as to permit the fall of the water level in the water line below that of the water level in the well regardless of the 45 pressure remaining in the air line. This is of particular advantage for as soon as the pumping operation ceases, the water drops in the water line or pipe 11 to a level in that of the air line or pipe 17 whereby the cylinder 50 2 is emptied of all water and thus preventing freezing therein and the cistern 1 is of such a depth as to cause the water level within the water line or pipe 11 and the air line or pipe 17 to be at a point below the 55 surface line as to thoroughly prevent freezing of the water therein.

While the petcock 8, hereinbefore referred to, may be properly adjusted to control the degree of pressure within the air line, this 60 pressure may be further regulated by the size of the openings in the reticulated nozzle 22. I also interpose in the water pipe 11 just back of the check valve 14 a petcock 23 which upon being opened is adapted to facilitate the return of the water after the

70 pumping operation to its level and also affords a coupling whereby air may be pumped for other purposes as it will be readily understood that when such petcock 23 is opened, the suction created by the piston 5 will have no effect upon the water within the cistern or well.

75 It is thought to be obvious that my improved pumping mechanism is of such a character that should from any cause the suction fail to work that water may be elevated through the action of the air alone and should from any cause the air fail to work that the water may be elevated entirely by suction.

80 From the foregoing description it is thought to be obvious that a pumping mechanism constructed in accordance with my invention is of an extremely simple and comparatively inexpensive nature and is particularly well adapted for use by reason of the convenience and facility with which the water may be conveyed or elevated and of the certainty with which the water within the mechanism is safe-guarded against 85 freezing and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

90 I claim:

95 1. A pumping mechanism comprising a cylinder, a piston therein mounted for recurrent movement, a water line in communication with the cylinder below the piston, an air line in communication with the cylinder 100 above the piston, such water line and air line being disposed in substantial continuity and being adapted to extend downwardly within a cistern and terminating below the water level therein, and a movable air vent below 105 the water level in the cistern through which the air within the air line is adapted to escape.

110 2. A pumping mechanism including a cylinder, a piston mounted therein for recurrent movement, a water line in communication with the cylinder below the piston, and an air line in communication with the cylinder above the piston such air line and water line being formed in substantial continuity and being adapted to be extended within a cistern below the water line, the air line having 115 its lower extremities provided with an enlargement of greater capacity than the water line.

120 3. A pumping mechanism including a cylinder, a piston mounted therein for recurrent movement, a water line in communication with the cylinder below the piston, and an air line in communication with the cylinder 125 130

- der above the piston such air line and water line being formed in substantial continuity and being adapted to be extended within a cistern below the water line, the air line adjacent its connection with the water line being of an increased diameter relative to the remaining portion of the air line for a predetermined length and of a diameter in excess of the water line.
- 10 4. A pumping mechanism comprising a cylinder, a piston within the cylinder mounted for recurrent movement, said cylinder being provided with a check controlled air inlet above the piston, a water line in communication with the cylinder below the piston, such water line and air line being disposed in substantial continuity and being adapted to extend downwardly within a cistern and terminating below the water level therein, and a movable air vent below the water level in the cistern through which the air within the air line is adapted to escape.
- 15 5. A pumping mechanism comprising a cylinder, a piston therein mounted for recurrent movement, a water line in communication with the cylinder below the piston, an air line in communication with the cylinder above the piston, such water line and air line being disposed in substantial continuity
- 20 and being adapted to extend downwardly 30 within a cistern and terminating below the water level therein, a movable air vent below the water level in the cistern through which the air within the air line is adapted to escape, and means for controlling the degree of air pressure created by the outward stroke of the piston.
- 25 6. A pumping mechanism comprising a cylinder, a piston mounted therein for recurrent movement, a water line in communication with the cylinder below the piston, an air line in communication with the cylinder above the piston, such water line and air line being disposed in substantial continuity and being adapted to extend downwardly within 35 a source of supply and terminating below the water level therein, a check controlled induction member in communication with the water line, and a controllable vent in communication with the water line above 40 the level of the source of supply.
- 30 In testimony whereof I hereunto affix my signature in the presence of two witnesses.
